UNITED STATES PATENT OFFICE

122,073

DESIGN FOR A SWING FRAME

Frank C. Castelli, Carroll Park, Pa.

Application May 1, 1939, Serial No. 84,714

Term of patent 7 years

To all whom it may concern:

Be it known that I, Frank C. Castelli, a citizen of the United States, residing at Carroll Park, in the county of Delaware and State of Pennsylvania, have invented a new, original, and ornamental Design for a Swing Frame, of which the following is a specification, reference being had to the accompanying drawing, forming a part thereof.

The single figure in the drawing is a perspective view of a swing frame showing my new design. The characteristic feature of my design resides in the combination of the cucullate top and the diverging legs. The other side of the cucullate top is the same as the side shown.

I claim:

The ornamental design for a swing frame, as shown and described.

FRANK C. CASTELLI.
